DESIGN FOR A TEXTILE FABRIC OR THE LIKE

Application filed February 3, 1933. Serial No. 47,094. Term of patent 3½ years.

To all whom it may concern:

Be it known that I, WILLARD D. The figure is a plan view of a textile fabric showing my new design.

The area within the dot and dash lines

shows one complete unit of the design. The repeats are arranged in vertical rows and adjacent vertical rows are one-half a complete unit offset so that the angle of the complete unit indicated by letter A corresponds with angle B of one of the repeats in an adjacent vertical row.

I claim:

The ornamental design for a textile fabric or the like as shown and described.

In testimony whereof I have signed this specification.

WILLARD D. ROBERSON.
